UNITED STATES PATENT OFFICE.

SAMUEL E. KEENER, DECEASED, LATE OF CLAY CENTER, KANSAS, BY WILLIAM E. KEENER, ADMINISTRATOR, OF CLAY CENTER, KANSAS, ASSIGNOR TO THE KEENER BURNER COMPANY, OF CLAY CENTER, KANSAS, A CORPORATION.

VAPOR-BURNER.

1,191,795.

Specification of Letters Patent. Patented July 18, 1916.

Application filed December 22, 1915. Serial No. 68,290.

To all whom it may concern:

Be it known that SAMUEL E. KEENER, now deceased, late a citizen of the United States, residing at Clay Center, in the county of 5 Clay and State of Kansas, invented certain new and useful Improvements in Vapor-Burners, of which the following is the specification, reference being made to the accompanying drawings, which are hereby made a 10 part hereof.

This invention relates to vapor burners for heating, cooking, and steam generating purposes and the objects are to provide a burner which will most completely consume 15 the fluid and prevent the filling up of the passages and interfering with the free flow of such fluid.

In the accompanying drawings is illustrated a circular shaped burner, but it is 20 proposed to vary the shape and structural details as may be found necessary but without departing from the mechanical principles involved.

The objects mentioned are accomplished 25 by means of the construction hereinafter described and illustrated in the accompanying drawings, in which:—

Figure 1 is a plan view of the improved burner; Fig. 2, a vertical sectional view of 30 same; Fig. 3, a plan view of the inverted air-chamber and air-pipes combined; Fig. 4, a perspective view of the removed deflector, and Fig. 5, a detail view in perspective of the deflector in side elevation a quarter turn to that in Fig. 2.

Similar numerals of reference indicate like parts throughout the several views.

The burner consists of the base A, dome or cap B, and deflector C. The base is provided with a threaded opening, preferably 40 through the bottom thereof, into which is fitted supply pipe f connecting with stub-tube n which is covered by deflector C provided with projection e extending into the 45 opening in tube n. The projection e is provided with lateral ribs or lugs k k and l l continuing at right angles on under surface

of the deflector C. These ribs or lugs, of course, could be attached as well to the inside and top of stub-tube n. One pair of 50 the horizontal ribs, as j j, on opposite sides of the deflector, are made somewhat wider vertically than the complement pair, as i i, and as the deflector rests upon the wider ones, the action of the fluid passing the deflector causes it to slightly rock, thus by 55 agitation keeping the passage through tube n and the under surface of the deflector free from the accumulation of sediment. For convenience and economy of construction 60 the air-pipes c c c c are cast integral with the dome or cap B. Each of the air-pipes opens into the air-chamber m. Through the base A are holes opening into the air-pipes and through these holes and pipes c c c c the 65 intensity of the flame is controlled by regulating the draft of air therethrough in any ordinary manner. Where both gas and oil are available the supply pipe f may be fitted with a T joint h and each connecting pipe 70 provided with a valve g by means of which either fluid may be supplied or cut off as desired.

What is claimed as new is,—

A burner of the class described comprising 75 a base provided with an opening therethrough through which to supply fuel to said burner, means for supplying fuel through such opening, a deflector supported above said opening and resting upon ribs or 80 lugs placed on opposite sides of the under surface of said deflector whereby the deflector is permitted to rock thereon, an air-chamber above said deflector, air-pipes connecting with said air-chamber, the opposite 85 ends of said air-pipes communicating with openings through said base, and means for supplying air to said pipes.

WILLIAM E. KEENER,
Administrator of the estate of Samuel E. Keener, deceased.
